E. C. DE SEGUNDO

METHOD OF DEFIBRATING COTTON SEED AND OTHER FIBER BEARING MATERIAL

Filed Oct. 31, 1922

UNITED STATES PATENT OFFICE.

EDWARD CARSTENSEN DE SEGUNDO, OF LONDON, ENGLAND.

METHOD OF DEFIBRATING COTTON SEED AND OTHER FIBER-BEARING MATERIAL.

Application filed October 31, 1922. Serial No. 598,170.

To all whom it may concern:

Be it known that I, EDWARD CARSTENSEN DE SEGUNDO, a subject of the King of Great Britain, residing in London, England, have 5 invented a certain new and useful Improved Method of Defibrating Cotton^{*} Seed and Other Fiber-Bearing Material, of which the following is a specification.

My invention consists in an improved 10 method of defibrating cotton seed and other fiber bearing material, as for instance the decorticated hulls of cotton seed, and of segregating the detached fibers.

In carrying out the improved method, the 15 material to be treated is caused to pass through a defibrating zone under the action of gravity and centrifugal force, the rate of the movement of the material through such zone being regulated according to the 20 degree to which it is desired to defibrate the material and the regulation being assisted by varying at will the cross sectional area of the zone. The discharge of the defibrated material from the defibrating zone is arranged 25 to be free and unhindered as far as practicable.

Segregation of the detached fibers may be effected in accordance with the disclosure in my U. S. Patent No. 1,329,838, Feb. 3, 1920, 30 by employing a plenum of air directed by the action of the defibrating elements in the defibrating zone, but in the present invention a more effective and expeditious segregation of the fibers results from the employment of a current of air established by any mechanical or positive means in contradistinction to that described in said patent. The current of air is caused to traverse the mass of material under treatment in a direction different from that in which the 40 defibrated material is discharged from the defibrating zone, free access of air to the said zone being permitted in order to promote the passage of air into and through the zone in obedience to whatever method 45 may be adopted for producing such current of air.

The accompanying diagrammatic drawing 50 illustrates apparatus adapted for carrying out the improved defibrating method, Fig. 1 being a vertical section of one form of a defibrating chamber; and Figs. 2 and 3 being fragmentary sections, each showing a modified form of the defibrating chamber, 55 and Fig. 4 is a detail view showing the

manner of adjusting the defibrating member on its shaft.

The apparatus as illustrated in Fig. 1 comprises a defibrating chamber *a*, which may be of upright conical form as indicated at 60 *a* in Fig. 1, or cylindrical as shown at *p* in Fig. 2, or partly cylindrical and partly conical as depicted at *q* in Fig. 3, with an apertured lower end *a'*. The inner surface of the chamber side wall may be smooth or 65 rough and may be furnished with projecting parts. In the defibrating chamber is a rotatable member *b*, operated by a shaft *c* which passes through the lower end of the defibrating chamber and can be rotated in any 70 convenient manner. The member *b* attached to the shaft *c* may be of any form suitable for carrying a number of defibrating devices *d*.

The rotatable member *b* is, preferably, 75 closed at the top so that the seed or other material to be treated, when fed from above, may be constrained to pass through the annular space *e* between the rotatable member and the walls of the defibrating chamber *a* 80 and be exposed to the action of the defibrating devices *d* during its passage through the machine. The annular space *e* constitutes the defibrating zone above alluded to.

For the purpose of varying the cross sectional area of the defibrating zone, the position of the member *b* relative to the end *a'* of the defibrating chamber *a* may be adjustable, for instance by arranging the said member to be slideable along the shaft *c* and 90 keying it in any adjusted position as shown by Fig. 4 at *c'*.

On the top of the defibrating chamber *a* and coaxially therewith is arranged and fitted a cover or hood *f*. Mounted in or on the 95 hood are sieve-like devices *g* that serve as sifters and outlets for the escape of very short fibers and of dust or other foreign matter which may be carried up in mechanical mixture with the separated fibers, such 100 dust and very short fibers or foreign matter tending to be expelled through the sieve-like devices owing to the action of the current of air that is caused to pass through the machine. Such dust or short fibers may be 105 allowed to settle within one or more compartments or chambers *j* formed for the purpose around the outside of the hood. In the outer wall of this compartment are doors or shutters *k* to permit of the removal, from 110

time to time, of any dust or short fibers or other foreign matter deposited therein.

Dependent within the hood or cover *f* is a funnel or conduit *l* which has its lower end 5 opening into the chamber *a* and is arranged preferably centrally of said chamber. The material to be treated may be introduced into the interior of this funnel in any convenient manner. The portion of the funnel 10 which passes down through the hood and terminates at a suitable level with respect to the upper part of the defibrating chamber *a* forms an annular space *m* between it and the inner surface of the hood. This annular 15 space should be of such a width as to ensure the ascent of the uprising fiber-laden air current without undue friction, while avoiding the formation of eddy currents to any serious extent, thus promoting the efficient 20 action of the sieve-like screens over which the fiber-laden air-current passes and promoting efficient expulsion of the detached fibers from the machine and their delivery to the fiber-depositing chamber. The annular 25 space *m* is open at its lower end to the interior of the defibrating chamber and communicates through its upper end with any conveniently disposed conduit *n* in which is mounted an evacuating device, such as the 30 fan *o*, that is arranged to be driven in any suitable manner for drawing in air through the openings at the bottom of the chamber *a* and to cause the current of air to pass 35 through the annular space or defibrating zone *e* for the purpose of conveying upwardly to the conduit *n* the detached fibers, which are carried away by the evacuating device to any desired point.

The funnel member *l* may be supported in 40 any suitable manner, for instance, by brackets *r* fixed to the top of the defibrating chamber *a*.

In the defibrating operation, the rotatable member *b* carrying the devices *d* is set in 45 motion, whereupon the seeds or other material to be defibrated are fed into the funnel *l* and delivered to the defibrating chamber *a* and are impelled radially outwards towards the wall of the chamber by centrifugal 50 force and subjected to the action of the devices *d*. During their passage through the machine the seeds tend to be held in suspension while being acted upon by the devices *d* owing to the combined action of 55 the rotating devices assisted by the conical form of the wall of the defibrating chamber. The air entering through a central opening

a' in bottom *a'*, flows at first radially outwards below the devices *d* and then upwardly carrying with it the separated fibers. 60 On its passage through that part of the annular space *m* which is opposite the sieve-like devices *g*, the current of air, laden with fiber and dust delivers dust and very fine 65 fibers through the sieve-like devices *g*. In this manner a cleaning of the detached fibers may be effected. The fibers are carried by the current of air and are forwarded by the evacuating device *o*, and eventually segregated in any convenient manner. 70

The defibrated material finds its way out through a suitably arranged outlet *t* provided for the purpose in the bottom or side wall of the defibrating chamber. The wall of the hood *f* should be of such a height that 75 no defibrated material will be lifted by the current of air sufficiently to pass into the conduit *n* and be carried away by the evacuating device.

Having thus described the nature of the 80 said invention and the best means I know of carrying the same into practical effect, I claim:

A method of defibrating cotton seed, de-corticated cotton seed hulls, and other fiber-bearing material, which consists in causing the material to be treated to pass through a defibrating zone under the action of gravity and centrifugal force and causing defibration to occur during the movement of the material through such zone, the rate of movement of the material operated upon being regulated according to the degree to which it is desired to defibrate the material by varying the cross sectional area 90 of the zone and freely discharging the defibrated material from the defibrating zone and subjecting the material operated upon to a mechanically and positively produced current of air which is caused to traverse 100 the mass of material throughout the whole of the defibrating zone in a direction opposed to that in which the material is moving as a whole through the defibrating zone 105 so that the fibers detached from the material throughout said zone are continuously carried away by the current of air during the defibrating action and discharged in a direction substantially opposed to the direction of motion of the mass of material 110 through the defibrating zone.

In testimony whereof I have signed my name to this specification.

EDWARD CARSTENSEN de SEGUNDO.
